United States Patent Office

Des. 208,675
Patented Sept. 19, 1967

208,675

DIAPER PAIL

Norman S. Gardner, New Rochelle, N.Y., assignor to Joy Plastics, Inc., New York, N.Y.

Filed Oct. 22, 1965, Ser. No. 87,767

Term of patent 14 years

(Cl. D58—17)

FIG.1

I claim:

The ornamental design for a diaper pail, as shown.
